UNITED STATES PATENT OFFICE.

ARTHUR A. ERB, OF DENVER, COLORADO.

ARTIFICIAL LIMB.

1,400,042.

Specification of Letters Patent. Patented Dec. 13, 1921.

Application filed October 17, 1921. Serial No. 508,370.

To all whom it may concern:

Be it known that I, ARTHUR A. ERB, a citizen of the United States, residing at the city and county of Denver, and State of Colorado, have invented certain new and useful Improvements in Artificial Limbs; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to the improvement of artificial limbs, and has particular relation to the improvement of the ankle joint therefor, or jointed connection between the foot and the leg.

The objects of my invention are to provide a simple and effective ankle joint of improved construction and arrangement of parts, whereby a natural movement of the foot may be attained, to so construct my improved ankle joint as to insure the same notwithstanding great strain and wear, and obviate the necessity of employing the usual heel cord or cords, and to produce other improvements, the detail of construction of which will be more fully pointed out hereinafter. These objects I accomplish in the manner illustrated in the accompanying drawing in which—

Figure 1 is a central longitudinal section through the foot and the lower portion of the leg;

Fig. 2 is a transverse longitudinal section taken on line 2—2 Fig. 1;

Fig. 3 is a section of my improved ankle joint taken on line 3—3 Fig. 2;

Fig. 4 is a section taken on line 4—4 Fig. 3; and

Fig. 5 is a detail showing a slight modification.

The same reference characters will be used to indicate the same parts throughout the several views.

Numeral 1 represents an artificial foot body, the upper side and rear portion of which is provided with an elongated recess 2. The lower end 3 of the leg portion 4 projects into the longitudinal recess 2 and is hingedly connected to the foot member 1 by means of my improved ankle joint, which comprises two U bolts 5 and 6, the former of which passes through suitable

openings 7 into a recess 8 in the bottom of the foot member, where it is held in place by means of nuts 9 and a strap 10. The upper U bolt 6 passes upwardly through the lower portion 3 of leg member 4, in the manner clearly shown in Figs. 1 and 2, and is held in place by means of nuts 11 and strap 12, in the same manner as bolt 5. In order to provide a substantial and durable bearing upon which the relative movement of the foot and the leg may take place, I provide a tubular cylindrical member 13, which is provided on its outer surface and approximately midway between its ends 70 with an enlarged portion 14, which contains a groove 15 for the reception of the arcuate connecting portion 16 of U bolt 6 (Fig. 3). U bolt 5 has a straight part 17 connecting the two sides of the U, and is located 75 within the tubular bearing member 13 in the manner shown in Figs. 2 and 3. The upper side of member 13 is provided with an elongated opening 18 of sufficient width and length to receive the U bolt 5, and 80 diametrically opposed to opening 18 are two transversely elongated holes 19 (Fig. 4) for the reception of the two arms of U bolt 5. Within cylindrical member 13 is a cylindrical bearing member 20, which is 85 provided in its upper surface with a longitudinal channel 21, which is of a size and depth to receive the transverse part 17 of bolt 5. Member 20 is also provided with two holes 22 which are of such size as to permit 90 the arms of bolt 5 to slide therein.

It is evident that when my hinge or joint is assembled, as shown in the drawings, bolt 5 can be rocked to the extent permitted by holes 19. Lower or foot member 1 is 95 provided in the bottom of recess 2 with a depression 23 for the reception of the cylindrical tubular member 13, and the lower surface of leg member 3 is also provided with a similar depression 24. In order 100 to positively prevent the cylindrical member 25 from rotating in depression 24, I provide the leg member 3 with a projecting portion 25, which engages in the elongated opening 18.

In order to provide the requisite resiliency, I place a rubber cushion 26 in front of the pivot, and a rubber plug 27 to the rear of the pivot. I may also provide a rubber cushion 28 to the rear of the pivot, but usually plug 110 27 is sufficient.

Where the stump is very long, necessitat-

ing a very short lower leg portion 3, I substitute for **U** bolt 6 two plate members 29 (Fig. 5) which have tapered holes 30 which coöperate with corresponding tapered portions on the ends of cylindrical tubular member 113. Members 29 are held in place by means of screws 31, which engage the internally screw-threaded ends of tubular member 113. Holes 32 are provided in members 10 29 for the reception of screws whereby it is secured to the outside of the lower leg member.

From the above it will appear that I have produced an ankle joint hinge that is of 15 simple, rigid and durable construction, and which possesses great strength. I wish to particularly point out that the cylindrical tubular member is of great strength, having an elongated opening 18 at its top which is 20 only of sufficient size to permit the **U** bolt 5 to be inserted therethrough. Cylindrical member 20 is introduced into tubular member 13 through the end thereof and not from the top, as has been done before. This 25 results in a construction in which member 13 retains the greater portion of its strength and substantially insures that this member will not break. I consider the structural feature just pointed out to be of great practical importance, as it results in an article 30 of superior strength and greater adaptability to limbs of different kinds.

Having now described my invention, what I claim is—

- 35 1. As an article of manufacture, a detachable ankle joint for artificial limbs, comprising in combination an open-ended tubular, substantially cylindrical, member, a longitudinally elongated opening in one side of 40 said member, a longitudinally grooved cylindrical member adapted to be inserted into said tubular member through the open end thereof, a **U**-shaped bolt encircling said

tubular member substantially midway between its ends, a pair of spaced transversely longitudinal openings in the side of said tubular member opposite the longitudinally elongated opening, a pair of spaced openings in said cylindrical member, and a **U** bolt having its arms projecting through the openings in the tubular and the cylindrical members.

2. An ankle joint for artificial limbs, comprising in combination a tubular, substantially cylindrical, member having open ends, a longitudinally elongated opening in one side of said member, an enlarged portion between the ends thereof, a groove in said enlarged portion, a cylindrical member adapted to be inserted into said tubular member through the open end thereof, said cylindrical member having a longitudinal channel in one side thereof, and two spaced openings from said channel to the other side, a pair of spaced transversely elongated openings in said tubular member, a **U** bolt encircling said cylindrical member and co-operating with said groove, a **U** bolt having its arms passing through the spaced openings in the tubular and cylindrical members, and having its transverse portion in the channel in the cylindrical member.

3. An ankle joint for artificial limbs, comprising in combination a tubular member having open ends, a cylindrical member adapted to be inserted into said tubular member through one of the open ends, a transversely elongated hole in said tubular member, a bolt passing through said elongated opening and secured to the cylindrical member, and means for non-rotatably securing said tubular member to a part of an artificial limb.

In testimony whereof I affix my signature.

ARTHUR A. ERB.
